UNITED STATES PATENT OFFICE.

CHARLES W. ROOD, OF BRITT, IOWA, ASSIGNEE TO IDEAL EXCAVATING COMPANY, OF BRITT, IOWA, A COPARTNERSHIP.

EXCAVATING APPARATUS.

SPECIFICATION forming part of Letters Patent No. 767,765, dated August 16, 1904.

Application filed January 16, 1904. Serial No. 189,352. (No model.)

To all whom it may concern:

Be it known that I, CHARLES W. ROOD, a citizen of the United States, residing at Britt, county of Hancock, State of Iowa, have invented a certain new and useful Improvement in Excavating Apparatus; and I declare the following to be a full, clear, and exact description of the invention, such as will enable others skilled in the art to which it pertains to make and use the same, reference being had to the accompanying drawings, which form a part of this specification.

My invention relates in general to excavating apparatus, and more particularly to machines for digging ditches for irrigating and drainage purposes.

Although it is desirable that a drainage or irrigating ditch should be uniform in depth and have a constant degree of slope, yet it is customary in the operation of apparatus for cutting ditches for the depth and slope of the ditch to depend upon the skill of the operator and not upon a fixed gage. Consequently it is practically impossible to give the ditch as it progresses a uniform depth and slope.

My invention has for its primary object the production of an apparatus for cutting trenches or ditches the operation of which will cut a ditch having a uniform slope and unvarying depth.

A further object of my invention is to provide an excavating apparatus which may be so adjusted as to dig a ditch of any desired uniform depth below the surface of the earth and which will impart to the ditch a uniform slope.

A still further object of my invention is to provide an apparatus of the character described which will be comparatively simple, 40 in construction, inexpensive in manufacture, and efficient in operation.

My invention, generally described, consists in a supporting-frame adapted to rest upon the ground at either side of the ditch, a transverse guide vertically adjustably supported upon the frame and conforming to the desired cross-section of the ditch, a shovel engaging said guide to remove the earth to form a ditch, and means mounted upon the sup-

porting-frame for moving said shovel transversely across the ditch.

My invention will be more fully described hereinafter with reference to the accompanying drawings, in which the same is illustrated in a convenient and practical form, and in which—

Figure 1 is an end elevational view showing the apparatus in operative position with relation to a ditch which is being cut; Fig. 2, a plan view; Fig. 3, an enlarged sectional view of the means for adjusting the grade of the cut; and Figs. 4 and 5, enlarged detail views, the latter being a sectional view on line 5 5 of the former.

The same reference characters are used to designate the same parts in the several figures of the drawings.

A' and A² indicate timbers which are placed upon the ground at either side of the ditch and which serve as tracks upon which rests the supporting-frame of the apparatus.

B' and B² indicate longitudinal sills of a supporting-framework, which rest upon the timbers A' and A². Any desired number of transverse sills are mounted upon and rigidly secured to the longitudinal sills B' and B². Extending upwardly in an inclined direction from the transverse sills b' and b² from points adjacent to the longitudinal sills B' are beams b³ and B⁴, which support at their upper ends a beam B. Beams b⁴ and B⁴ extend upwardly from the transverse sills b' and b² at points above the longitudinal sill B² and are united at their upper ends to the inclined beams b³ and B⁴, adjacent to the top beam B. Posts C' and C² are mounted upon the side sill B' at points above the ends of the transverse sills b' and b². The tops of the posts C' and C² are united by a cross-beam C. Vertical screw-threaded shafts D' and D² loosely extend through the bearings formed in the cross-beam C, adjacent to the posts C' and C², and engage bearings c' and c² at their lower ends, supported upon the posts C' and C², respectively, near their lower ends. The upper ends of the shafts D' and D² are provided with levers d' and d² for rotating the same. A bar D extends between the shafts D' and D² and is provided with screw-

threaded heads $\text{d} \text{d}$ at its opposite ends, which are engaged by the screw-threads on the shafts. Extending beneath the bar D are parallel I-beams E' and E^2 , which are supported by the bar D by means of straps e' and e^2 , extending around the bar D . The I-beams E' and E^2 incline upwardly and extend to one side of the supporting-framework of the apparatus. The upper ends of the I-beams are bifurcated and separated vertically, as shown in Fig. 1. The outer ends of the I-beams E' and E^2 are supported by struts e^3 and E^3 , extending to the inclined beams b' and B^2 , respectively, to which they are secured at points adjacent to their upper ends.

To the lower ends of the I-beams E' and E^2 are pivotally secured parallel channel-beams F' and F^2 , the latter comprising horizontal lower portions and upwardly and outwardly inclined end portions. The ends of each of the channel-beams are united by cross-beams $\text{F}'\text{F}^2$, between which and various points of the channel-beams extend strengthening-struts f' , f^2 , and f^3 . The free ends of the channel-beams are united by a rod F^3 , to which is pivotally connected the lower end of a rod O , which extends upwardly and which is supported between the two parts O' and O^2 of a friction-clutch mounted upon the beam B . Any suitable form of clutch may be employed for gripping the rod O , and thereby supporting the ends of the channel-beams opposite to their pivotal connections with the I-beams. I have shown in Figs. 4 and 5 the details of a preferred form of clutch which consists in the two gripping portions O' and O^2 , which are located between two plates P' and P^2 , the former being rigidly secured to the top beam B of the supporting-framework. The plates P' and P^2 are united at their opposite sides by toggle-links q' and q^2 . A spring P is interposed between the plate P^2 and the bar p , the tension of such spring tending to grip the two parts of the clutch together, owing to the rods p' and p^2 , which are connected at their lower ends to bearings upon the plate P' and which extend at their upper ends through the bar p . The tension of the spring P may be regulated by nuts located upon the screw-threaded ends of the rods p' and p^2 , which project through the bar p . A lever Q is rigidly connected to one of the links q' of the toggle and is provided with holes q at its ends, by means of which an operating-rod r is secured to the lever Q . The lower end of the rod r is pivotally connected to a treadle R , suitably mounted upon the supporting-framework of the apparatus.

The inwardly-projecting flanges of the channel-beams F' and F^2 serve as tracks to support trolley S , from which depend a shovel or bucket H for removing the earth to form the ditch. Referring particularly to Fig. 3, K' designates an axle of one of the trolleys, on the ends of which are fixed wheels $\text{k}' \text{k}^2$. Supported by

the axle K' is an I-beam H' . Any suitable supporting means may be provided for uniting the I-beam to the axle—such, for instance, as the staples $\text{h} \text{h}$, surrounding the axle adjacent to the wheels on the ends thereof and passing through openings in the flanges of the I-beam. The ends of the staples which extend through the openings in the flanges of the I-beam are provided with nuts or other retaining devices. Two or more trolleys and I-beams are preferably provided to support the shovel, as indicated in Fig. 1, the upper wall of the shovel being rigidly secured to the bottom flanges of the I-beams by bolts or other suitable fastening devices, as indicated in Fig. 3. The shovel H is formed open at its front end and closed at its top, bottom, back, and at both sides. The inwardly-projecting flanges of the I-beams E' and E^2 form a continuation of the inwardly-projecting flanges of the channel-beams F' and F^2 and serve to guide the trolley-wheels which support the shovel and direct the shovel to a point above the spoil-pile, as indicated in Fig. 1. The lower portions of the bifurcated ends of the I-beams E' and E^2 are inclined downwardly, so that the earth will fall by gravity from the shovel.

The shovel H is drawn transversely across the ditch by means of a cable L , secured to the front end thereof, which is guided by rollers $\text{l} \text{l}$, supported by the horizontal portions of the channel-beams. A guide-roller l' is mounted upon a shaft which is journaled in the upper portions of the bifurcated ends of the I-beams E' and E^2 . The propelling-cable L passes around such guide-roller, and thence around another guide-roller l^2 , supported near the top beam B of the supporting-framework. The cable L then passes to a drum L' , around which it is wound. Any suitable motive power may be provided for rotating the drum L' —such, for instance, as a boiler N , mounted upon a platform b' , supported by the side sills B' and B^2 of the framework. The shovel or dipper H is propelled backwardly across the ditch by means of a cable M , secured to the rear end thereof and passing around a guide-pulley m' , journaled upon the rod F^3 , which is supported at its opposite ends by the ends of the channel-beams. The cable M then passes around a guide-pulley m^2 , supported opposite to the top beam B , and then passes to a drum M' , upon which it is wound. The same motive power which operates the drum L' may be utilized for operating the drum M' .

The operation of my invention is as follows: The side sills B' and B^2 are placed upon the longitudinal supporting-beams A' and A^2 , grease being preferably interposed between the same, so as to facilitate the supporting-frame being drawn longitudinally above the ditch as the work progresses. The channel-beams F' and F^2 serve as guides to determine

the depth of the cut or ditch and also the slope thereof. By rotating the screw-shafts D' and D'' the bar D, supported thereby, may be raised or lowered and the ends of the channel-beams which are pivotally supported to the lower ends of the eye-beams thereby raised or lowered and the distance which the guides depend below the supporting-frame thereby adjusted. When the bar D has been 10 adjusted to conform to the desired depth of the ditch, the opposite ends of the channel-beams are gradually lowered from the position shown in dotted lines in Fig. 1 by manipulating the clutch, which engages the rod O 15 as the successive transverse movements of the shovel deepen the ditch. The guide for the shovel, which comprises the channel-beams and transverse beams F, uniting their ends together with the strengthening-struts, is swung 20 upwardly into the position shown in dotted lines in order to elevate the same above the surface of the ground and permit the apparatus to be located in position to commence cutting the ditch. The guide is swung into such 25 position by means of the cable M, which when wound upon its drum M' draws the shovel H to the ends of the channel-beams and then swings upwardly the guide about the points of pivotal connections between the channel- 30 beams and the I-beams. In order to permit such upward swinging movement of the guide, the treadle R is pressed down, thereby extending the toggles q' and q'' into the positions shown in Figs. 4 and 5, which compresses the spring P and permits the rod O to pass freely between the two parts of the clutch. The treadle R when released permits the 35 spring P to force the two parts of the clutch into tight engagement with the rod O, and thereby securely support the end of the 40 guide. The cutting of the ditch is accomplished by the cable L being wound upon the drum L' through suitable motive power which draws the shovel transversely across 45 the proposed ditch and fills the same with earth, which is dumped from the shovel when the latter is inclined by the bifurcated ends of the I-beams. As the earth is removed the 50 guide is gradually lowered by releasing the clutch by means of the treadle, so that the position of the guide above the earth is such as to force the shovel beneath the earth's surface at each transverse movement thereof. When the guide has been gradually lowered 55 until the free end thereof occupies a position corresponding to its pivotal support, the ditch has been cut at such point to the requisite depth, and the guide-frame is then swung upwardly into the position shown in dotted 60 lines in Fig. 1 and the supporting-framework moved along the ditch, so that the path of movement of the shovel will be above the earth which is to be removed to form a continuation of the ditch.

From the foregoing description it will be observed that I have invented an improved 65 excavating apparatus especially designed for digging ditches or trenches in which the cutting shovel or dipper is moved transversely and is forced below the earth's surface by means 70 of a transverse guide which may be adjusted vertically to determine the depth to be given the ditch and which is of a shape to impart to the ditch the desired degree of slope, so that the ditch will be dug to a uniform depth 75 and with a uniform degree of slope.

While I have described more or less precisely the details of construction, I do not wish to be understood as limiting myself thereto, as I contemplate changes in form, the proportion 80 of parts, and the substitution of equivalents as circumstances may suggest or render expedient without departing from the spirit of my invention.

Having now fully described my invention, 85 what I claim as new, and desire to secure by Letters Patent, is—

1. In an apparatus for digging ditches, the combination with a supporting-frame, of a shovel for removing the earth, means for moving 90 said shovel transversely across the ditch and means for directing the movement of said shovel to a point above the spoil-pile.

2. In an apparatus for digging ditches, the combination with a supporting-frame, of a 95 shovel for removing earth, means for moving said shovel transversely across the ditch, means for guiding said shovel in a path of movement conforming to the desired cross-section of the ditch and means for directing the movement of said shovel to a point above the spoil-pile. 100

3. In an apparatus for digging ditches, the combination with a supporting-frame, of a transverse guide conforming to the cross-section 105 of the proposed ditch, means for supporting said guide upon said frame, a shovel engaging said guide, means for moving said shovel transversely with respect to the ditch and means for directing the movement of said shovel to a point above the spoil-pile. 110

4. In an apparatus for digging ditches, the combination with a supporting-frame, of a transverse guide conforming to the cross-section 115 of the proposed ditch, means for vertically adjustably supporting said guide upon said frame, a shovel engaging said guide, means for moving said shovel transversely with respect to the ditch and means for directing the movement of said shovel to a point above the 120 spoil-pile.

5. In an apparatus for digging ditches, the combination with a supporting-frame, of a transversely swinging guide pivotally supported at one end, means for adjustably supporting the free end of said guide, a shovel 125 engaging said guide, and means for moving said shovel transversely with respect to the ditch.

6. In an apparatus for digging ditches, the combination with a supporting-frame, of a transversely-swinging guide pivotally supported at one end, means for vertically adjusting the pivoted end of said guide, means for vertically adjusting the free end of said guide, a shovel engaging said guide, and means for moving said shovel transversely across the ditch.
10. 7. In an apparatus for digging ditches, the combination with a supporting-frame, of a transversely-swinging guide pivotally supported at one end, a rod connected at its lower end to the free end of said guide, a clutch mounted upon the supporting-frame engaging said rod to retain the same in adjusted positions, a shovel engaging said guide, and means for moving said shovel transversely across the ditch.
15. 8. In an apparatus for digging ditches, the combination with a supporting-frame, a transversely-swinging guide pivotally supported at one end, means for vertically adjusting the pivoted end of said guide, a rod connected at its lower end to the free end of said guide, a clutch mounted upon the supporting-frame engaging said rod to retain the same in adjusted positions, a shovel engaging said guide, and means for moving said shovel transversely with respect to the ditch.
20. 9. In an apparatus for digging ditches, the combination with a supporting-frame, of a transversely-swinging guide pivotally supported at one end, means for adjustably supporting the free end of said guide, a shovel engaging said guide, a cable connected to one end of said shovel and engaging guides upon said supporting-frame, means for drawing said cable transversely across said ditch toward the free end of said guide whereby when the shovel reaches the end of the guide a con-
- tinued pull upon the cable will swing upwardly the guide.
10. 10. In an excavating apparatus, the combination with a supporting-frame, of a transverse guide conforming to the cross-section of the cut, means for supporting said guide upon said frame, a shovel engaging said guide, a track secured to one end of and forming a continuation of said guide for directing the movement of the shovel to a point above the spoil-pile, and means for propelling said shovel.
15. 11. In an excavating apparatus, the combination with a supporting-frame, of a transverse guide conforming to the cross-section of the cut, means for supporting said guide upon said frame, a shovel engaging said guide, a track secured to one end of and forming a continuation of said guide for directing the movement of the shovel to a point above the spoil-pile, means for vertically adjusting said track upon the supporting-frame, vertically-adjustable means for supporting the end of said guide opposite to its connection with said track, and means for propelling said shovel.
20. 12. In an apparatus for digging ditches, the combination with a supporting-frame, of a transverse guide conforming to the cross-section of the proposed ditch, means for supporting said guide upon said frame, a trolley engaging said guide, a shovel depending from and supported by said trolley, means for moving said trolley transversely along said guide, and means for directing the movement of said shovel to a point above the spoil-pile.
25. In testimony whereof I sign this specification in the presence of two witnesses.
